MEANS FOR TREATING FLUID

Filed Aug. 30, 1939

The image contains two technical drawings of a mechanical device, labeled Fig. 3 and Fig. 5.

Fig. 3 (Bottom Drawing): This is a side view of the device. It features a large cylindrical body (34) with a handle (33) attached to its side. A vertical rod (38) extends from the top of the cylinder. A lever system (37) is attached to the top of the cylinder, with a small gear (36) and a larger gear (35) meshing together. A small rectangular component (51) is mounted on the side of the cylinder. The number '3' is written vertically on the right side of the drawing.

Fig. 5 (Top Drawing): This is a cross-sectional view of the device. It shows a vertical assembly with various parts labeled with numbers. At the top, there is a circular dial or gauge (18) with markings. Below it, a gear (16) is meshed with another gear (15). A lever (10) is attached to the side of the gear assembly. A vertical rod (9) extends from the top. A small gear (17) is mounted on the side of the vertical rod. The numbers '5' and '3' are written vertically on the right side of the drawing.

MEANS FOR TREATING FLUID

Clair V. Swearingen, Chattanooga, Tenn.

Application August 30, 1939, Serial No. 292,738

3 Claims. (Cl. 210—29)

This invention aims to provide a novel means for treating fluids, a broad and general statement which will be better understood and made more specific as the description proceeds. The invention aims to provide novel means for delivering material in predetermined quantities, into a fluid, which may be under pressure greater than atmospheric pressure. The invention aims to supply a novel timing mechanism for controlling the delivery of the material. A further object of the invention is to supply novel means for actuating the dispensing device.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in top plan, a machine constructed in accordance with the invention, parts being sectioned away;

Fig. 2 is a side elevation wherein parts are in section;

Fig. 3 is an elevation showing the opposite side of the structure from that depicted in Fig. 2, parts being broken away;

Fig. 4 is a section of the casing and attendant parts, on the line 4—4 of Fig. 1;

Fig. 5 is a section on the line 5—5 of Fig. 1.

The frame of the machine comprises a base plate 1, on which is secured a prime mover 2, for instance an electric motor. A housing 3 is secured to the base 1, and in the housing a speed-reduction gearing 4 is mounted. The initial shaft 5 of the speed-reduction gearing is coupled to the shaft of the motor 2, the ultimate shaft 6 of the gearing being provided with a crank 7 (Fig. 3), the shafts 6 and 5 being arranged at right angles to each other.

Bearing posts 8 (Fig. 1) are mounted on the base plate 1, adjacent to one end thereof, and in the bearing posts, a driven shaft 9 is journaled for rotation, the shaft 9 being arranged parallel to the shaft 6 of the speed-reduction gearing 4. A radius arm 10 (Fig. 2) is mounted

to swing vertically on the driven shaft 9, adjacent to one end thereof. One end of a pitman 11 is pivoted (Fig. 3) to the crank arm 7 on the shaft 6 of the speed-reduction gearing 4, the opposite end of the pitman being pivoted to the intermediate portion of the radius arm 10 (Fig. 2). A pawl 12 (Fig. 3) is pivotally mounted on the radius arm 10. The pawl 12 is adapted to cooperate with a ratchet wheel 14, secured to the shaft 9.

For a purpose which will be made manifest hereinafter, a timing device is provided. The timing device includes a disk 15 (Fig. 1), disposed along side of the ratchet wheel 14, and mounted for swinging adjustment, at the will of an operator, on the shaft 9. Throughout a portion of its circumference, the disk 15 is supplied with a smooth track or cam 16, projecting a little way beyond the periphery of the ratchet wheel 14, as Fig. 3 will show, the track having a considerable extent, circumferentially of the ratchet wheel 14. Throughout the remainder of its circumference, the disk 15 is provided with a spur gear 17.

Figures 3 and 5 show that a short post 18 is secured on the base plate 1. A horizontal stub shaft 19 is secured in the post 18, and retains upon the post, an angle bracket 20, having an overhanging index 21.

A sleeve 22 is mounted on the stub shaft 19, for rotary adjustment at the will of an operator. At its inner end, the sleeve 22 is supplied with a pinion 23, which meshes with the spur gear 17 of the disk 15. At its outer end, the sleeve 22 is provided with a dial 24, the calibrations of which cooperate with the index 21 (Fig. 3). The dial 24 has a turning button 25. A clamp wheel 26 is threaded on the stub shaft 19, the hub of the clamp wheel engaging a friction washer 27 (Fig. 5), mounted on the stub shaft 19 and interposed between the hub of the clamp wheel 26 and the dial 24.

On that end of the driven shaft 9 which is remote from the dial 24 and associated parts (Fig. 1) is secured a crank arm 28. One end of a connecting rod 29 (Fig. 2) is pivoted to the crank arm 28, the opposite end of the connecting rod being pivoted to a slide 30. The slide 30 is mounted for right line reciprocation in a guide 32, which is a composite structure mounted on the base plate 1, and serving, so far as the present discussion is concerned, as a support for the slide 30. The detailed structure of the part 32,

and its functions other than that of a guide, will be brought out hereinafter.

To the guide 32 (Fig. 2) is fixed an upright bracket 33, carrying a horizontal stud 34, supporting a hopper 35, provided with a downwardly extended spout 36. A receptacle 37 is detachably connected at 38 to the bracket 33. In the bottom of the receptacle 37 is located a dispensing mechanism 39, which need not be described in detail, because it may be of any desired construction. Let it suffice to say that the dispensing mechanism 39 delivers a measured charge of material downwardly into the hopper 35, the dispensing mechanism including a rotary member 40, having outstanding fingers 41.

For the operation of the dispensing mechanism 39, there is provided a means actuated by and mounted upon the connecting rod 29. The actuating mechanism embodies a standard 42 (Fig. 2), fixed at its lower end upon the connecting rod 29. In the upper part of the standard 42, a hook-shaped arm 43 is held by a set screw 44 for longitudinal adjustment, if desired. The arm 43 is adapted to cooperate with the fingers 41 of the rotatable member 40, to actuate the dispensing mechanism 39.

What becomes of the material that passes downwardly through the spout 36, from the receptacle 37, under the control of the dispensing mechanism 39, is a manufacturer's choice, but the machine embodies a useful structure whereby the material may be introduced into fluid which is under pressure greater than atmospheric pressure. With that end in view, the part 32, hereinbefore referred to simply as a guide for the slide 30, may embody a casing 45 (Figs. 4 and 2), supported at 46 from the base plate 1, or mounted otherwise. The casing 45 is supplied at its ends with glands 47, and in the glands, the slide 30 has a fluid-tight sliding fit. The fluid to be treated leaves the casing 45, if desired, through a depending outlet pipe 48, but the casing is supplied with a plurality of circumferentially spaced plug closures 49, which permit the inlet and the outlet for the casing 45 to be disposed as occasion may require.

The slide 30 has a transverse opening 31 therethrough (Figs. 2 and 4), the opening receiving material discharged from the spout 36. The casing 45 has a horizontally projecting pin 50, whereunto a trough-shaped guard 51 is secured, by a clamp 52. The guard 51 extends part way around the feed slide 30 and prevents the material from dropping out of the opening 31 in the feed slide.

In practical operation, the motor 2 imparts rotation to the shaft 5 of the speed-reduction gearing 4, the pitman 11 being actuated from the shaft 6 of the gearing, by way of the crank arm 7. The pitman 11 swings the radius arm 10, the pawl 12 imparts rotation to the ratchet wheel 14, and the ratchet wheel rotates the driven shaft 9.

Noting Fig. 2, when the shaft 9 is rotated, the crank arm 28 actuates the connecting rod 29, the connecting rod delivering right line reciprocation to the feed slide 30. When the connecting rod 29 is operated, the working end of the arm 43 on the standard 42 is caused to move in a vertical orbit, and cooperates with the fingers 41 to turn the rotatable member 40 of the dispensing mechanism 39, material being delivered into the hopper 35, the material moving through the spout 36, into the opening 31 of the feed slide. When the feed slide is advanced, the material is fed into the casing 45 and mingles with the fluid

passing through the casing, an hermetic delivery of the material being effected, because of the glands 47, even though the fluid passing through the casing may be under pressure.

5 The operator can back off the clamp wheel 26 of Fig. 5, thus setting the dial 24 free for rotation, the dial being rotated by an operator, through the instrumentality of the hub 25. Rotation is imparted to the sleeve 22, and the pinion 23, co-operating with the spur gear 17 on the disk 15, rotates the disk, the cam or track portion 16 of the disk being shifted circumferentially of the ratchet wheel 14, with respect to the pawl 12 on the radius arm 10. The pawl 12 is adapted to ride upon the track 16, and the position of the track, considered relatively to the pawl, determines the number of impulses which the ratchet wheel 14 will receive, in any given time, from the pawl 12. The feed slide 30, therefore, may be given any desired number of reciprocations per minute, as a time-unit example, and it will be clear from Fig. 2 that there will be a corresponding number of discharges of material from the opening 31, into the fluid traversing the casing 45.

10 20 25 The machine may be used for treating fluid of any kind, such as sewage, water, either potable or for delivery into a boiler, steam, or industrial waste. The assembled material discharged from the receptacle 37, may be in the form of pills or pellets, measured quantities, capsules, containers, crystals, etc. The fluid may be treated to render it sterile, or for the purpose of deodorization, and if the fluid is water, a softening operation may be brought about. The uses mentioned are simply 30 35 illustrative examples, and impose no restrictions on the use of the device.

Having thus described the invention, what is claimed is:

1. In a machine for treating fluid, a dispensing mechanism including a rotatable member, a shaft supported for rotation, means for rotating the shaft, a crank on the shaft, a slide, means for supporting the slide for reciprocation, a pitman pivoted to the crank and to the slide, and an actuator carried by the pitman and including a part movable in an orbit into which a portion of the rotatable member extends and therefore engageable with said portion of the rotatable member, to operate the dispensing mechanism.

2. In a machine for treating fluid, a dispensing mechanism, means for operating the dispensing mechanism, comprising a shaft supported for rotation, a radius arm mounted to swing with respect to the shaft, means for swinging the radius arm, a ratchet wheel secured to the shaft, a pawl carried by the radius arm and engageable with the ratchet wheel, means for disengaging the pawl from the ratchet wheel throughout a portion of the stroke of the radius arm, and a device under the control of an operator for shifting the last-specified means, to vary the length of the period of engagement between the pawl and the ratchet wheel, and thereby to time the dispensing mechanism.

3. In a machine for treating fluid, a dispensing mechanism, means for operating the dispensing mechanism, comprising a shaft supported for rotation, a radius arm mounted to swing with respect to the shaft, means for swinging the radius arm, a ratchet wheel secured to the shaft, a pawl carried by the radius arm and engageable with the ratchet wheel, means for disengaging the pawl from the ratchet wheel throughout a portion of the stroke of the radius arm, comprising a rotatable member provided with a gear, and

with a track engageable with the pawl, and a device under the control of an operator for rotating said member, to vary the length of the period of engagement between the pawl and the ratchet wheel, and thereby to time the dispensing mechanism, said device including a shaft

supported for rotation and provided with a gear meshing with the gear of the rotatable member, and means operated by the last-specified shaft for indicating the amount that said shaft has been rotated.

CLAIR V. SWEARINGEN.
